UNITED STATES PATENT OFFICE

ERNEST G. LOWE, OF HARTFORD, ILLINOIS

MECHANISM FOR STRETCHING AND DRYING HIDES AND LEATHER

Application filed November 16, 1928. Serial No. 319,834.

My invention relates to the tanning industry and particularly to mechanisms used for stretching and drying hides and leather.

The chief object of my invention is to reduce the amount of manual labor and the time now required to stretch hides and leather, thereby reducing the ultimate cost of the product.

Another object of my invention is to lighten and make less onerous the manual labor still required.

The description of the mechanisms and their operations will be more fully understood by reference to the drawings, in which: Fig. 1 is a front elevation of the principal mechanism, showing a hide in place on a frame, partly broken away.

Fig. 2 is a view of the outer frame shown in Fig. 1.

Fig. 3 is a cross section along the line 3—3 in Fig. 1.

Fig. 5 is a side view of a holding member usually designated a toggle.

Fig. 6 is a top plan view of a toggle.

Fig. 7 is a bottom plan view of a toggle.

Fig. 8 is a detail view along the line 8—8 in Fig. 5.

Fig. 9 is a vertical sectional view of the holding members attached to the frame shown in Fig. 1 and Fig. 2.

During the process of tanning hides, it is necessary that the hides be thoroughly stretched in the process of drying. This process has heretofore consisted of the use of a large wooden board of very considerable weight on which the hide was stretched and tacked in place with carpet tacks. Not infrequently, when the hides began to dry and contract, the tacks pulled out.

When it is remembered that a hide of a very large animal may, when green, weigh from 100 to 200, or 300 pounds, it is obvious that a very large and heavy board is required and that the handling of the board when two hides are stretched on it is slow and laborious work requiring at least two men to handle.

To reduce this onerous work and also reduce the time required in handling the hides, I have produced, in my preferred method, a mechanism whereby it is never necessary to

manually lift and carry the heavy boards when the hides are in place thereon.

My preferred method consists of a rigid and strong outer frame 1 supported on an overhead track 2 by suitable attaching irons 3 carrying a wheel 4 rotatably mounted on an axle 5 so that the entire frame 1 can be readily moved horizontally along the track 2.

The lower part of the frame 1 is held against lateral movement by means of a projection 6 engaging a groove 7 in the floor board 8.

In order to prevent movement of the frame 1 longitudinally, door checks 9 of any suitable form are rigidly attached to the lower and outer edges of the frame 1 so that the plunger 10 of the door check 9 may be pressed down and instantly released by the operators.

Rotatably positioned within the main frame 1 is an inner frame 11, strong and substantially built, preferably of steel channel iron and reinforced by cross members 12 of flat bar metal.

The perforated sheet metal member 13 fills the entire space within the inner frame 11 between the reinforcing bars 12, and its marginal edges are rigidly attached to the enclosing frame as indicated in Fig. 3 at 14. The sheet metal member 13 may be spot welded, riveted, or otherwise securely attached to the frame 11.

The outer frame 1 is preferably made of square tubing, a section 15 of which is shown in Fig. 3.

As both sides of the inner frame are used for stretching hides or sides of leather, it is desirable that it be readily reversible for attaching the hides without burdensome labor.

The inner frame 11 is, therefore, rotatably mounted by a shaft 16 journaled in bearings 17 in the racks 18, vertically adjustable by means of the pinion 19, the rack 20, crank 21, mounted in brackets 22 rigidly attached to the outer frame 1.

When the buttons 23 are turned parallel with the frame 1, permitting rotation of the inner frame 11, the frame may then be raised or lowered to any convenient height best suited to the men stretching the hide in place, and of course, it can be rotated to a reverse

position for stretching a hide on the opposite side of the frame.

During this operation the door checks 9 are pressed rigidly against the floor, and when the operation is completed, the door checks are released and the entire frame carrying two hides or sides of leather is pushed along the track 2 out of the way, and each succeeding frame is likewise handled 10 without the strain and lifting that was necessary under the old method, with the result that not only much burdensome labor is eliminated, but much time is saved.

In order to hold the frame steady in a 15 horizontal position while the hides are being stretched thereon, I have provided a plurality of suitable hooks 24 pivotally attached to the outer frame 1 at one end and adapted to hook into and hold the inner frame in 20 adjusted positions.

As it is necessary that the hides be thoroughly stretched at every point, a special holding member, or toggle as it is known in the trade, is necessary to facilitate the 25 work. I have, therefore, designed a special toggle, shown in Fig. 5, which consists of a spring steel member 25 looped in a distorted U-shape so that the ends when brought together form the upper jaw 26 and lower 30 jaw 27 of a pair of pincers adapted to grip the edge of the hide or side of leather. The spring of the metal normally holds the jaws apart.

A cam 28 rotates about the axis 29 supported in the side members 30, which preferably are integral with the body of the toggle.

It is obvious that when the cam 28 is turned down, the pincers are closed in a manner to firmly hold the hide or side of leather.

40 A hook 31 is slidably adjustable by the rack 32 cut integral with the body of the toggle and the ratchet 33 normally held in position by the spring 34, attached to the 45 slideable member 35. When the toggle is affixed to the edge of the hide, as best shown in Fig. 1, the hide is stretched as far as possible and the hook 31 inserted in one of the 50 perforations 36; and in order to make the stretching of the hide more uniform, the hook 31 is made longitudinally adjustable.

It is evident that my mechanism in addition to saving a great deal of time in stretching the hides, removes an enormous amount of heavy, disagreeable work and, generally 55 facilitates the handling of the hides or sides of leather during this stage of the tanning process.

Having fully described my invention, what I claim as new and useful and desire to protect by Letters Patent is:

60 Mechanisms for stretching and drying hides and leather, comprising a transportable outer frame, a rotatable inner frame mounted within said outer frame, tracks for transporting said frames, means for transportably

suspending said frames from said tracks, means for shifting the axis of rotation of said inner frame in said outer frame, means for holding said inner frame in adjusted positions, means for holding hides and leather under tension within said inner frame, means for holding said frame and said mechanisms against longitudinal movement.

In witness whereof I have hereunto affixed my signature this 11th day of September, 75 1928.

ERNEST G. LOWE.
